CLAIM

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof; and,

FIG. 9 is another rear perspective view thereof, showing the mobile phone where a graphic is displayed.

The broken lines in the drawing depict portions of the mobile phone that form no part of the claim. The other broken lines in FIG. 9, showing a graphic, represent environmental subject matter only and form no part of the claimed design.

1 Claim, 9 Drawing Sheets
